SLEEVE PRESS

Ernest Davis, Syracuse, N. Y., assignor to The Prosperity Company, Inc., Syracuse, N. Y., a corporation of New York

Application January 7, 1948, Serial No. 1,020

11 Claims. (Cl. 223—57)

1

This invention relates to machines for ironing or pressing the sleeves of garments and particularly shirt sleeves of the general type shown in Davis Patent No. 2,420,818, issued May 20, 1947, and has for its object a spattulate form on which the sleeve is dressed and pressed in a sheet metal wrapper, U shaped in cross section, with the sides or wings of the U formation flatwise on the faces of press heads which have relative opening and closing movement, which form includes a body U shaped in cross section and arranged so that the bend of the U formation is opposed to and coacts with the bend of the wrapper, and a thin sheet metal expander within the body and shiftable to project through the open side of the body different distances to stretch the sleeve, the sides of the wrapper being shaped to conform to the body and the edges thereof on opposite sides of the expander, and to press flatwise on the side faces of the expander; all so that the sleeve is ironed or pressed throughout its entire surface except the thin line at the edge of the expander, where the sleeve is dry smoothed.

In pressing shirt sleeves, the sleeves are dressed on, or sleeved over, upright tapered forms, with the cuffs at the tops of the forms. The cuffs are pressed on other machines either before or after the sleeves are pressed. Usually, both sleeves are dressed on different forms at the same time and cooperate with different sets of press heads. However, the sleeves may be dressed one at a time on a single form. When the sleeve is dressed on its form, the cuff is clamped to the form at the top thereof, and held clamped while the sleeve is being smoothed, or pulled taut, by the operator on the form, and while the form is being shifted between the upright press heads.

When dressing the sleeves on the forms when the forms are out of their pressing positions between the press heads, the expanders are operated manually and latched in operated position by mechanism movable with the form.

The invention consists in the novel features and in the combinations and the constructions hereinafter set forth and claimed.

In describing this invention, reference is had to the accompanying drawings in which like characters designate corresponding parts in all the views.

Figure 1 is a side elevation of a sleeve press embodying this invention, parts being omitted.

Figures 2 and 3 are respectively fragmentary plan views showing the press heads closed on the

form and the expanders extended, or adjusted, out of the bodies of the form; and the press heads as open and the forms out from between the press heads with the expanders withdrawn into the bodies of the forms.

Figure 4 is an enlarged fragmentary isometric sectional view of the form.

Figures 5 and 6 are side elevations of the form, partly broken away, with the sleeves thereon shown in broken lines, showing the expander in normal and its extended position.

Figures 7 and 8 are enlarged plan views, partly broken away, of one of the forms with the sleeve thereon and the press heads, showing the follow-up movement of the expander to take up slack in the sleeve which develops at the edges of the body of the form while the pad on the body is being compressed before the press heads finally clamp onto the expander, the press heads being shown as open in Figure 7, and as closed in Figure 8.

Figure 9 is a plan view of the form with the sleeve thereon and the expander in retracted position.

The machine includes, generally, a suitable frame, two pairs of press heads, each pair including members 1, 2, having relative opening and closing movement, these being mounted on the frame in any suitable manner, a form 3 shiftable into and out of position between the press heads, a wrapper 4 for each pair of press heads, 2, the wrapper being U shaped in general form with the sides of the U formation overlying the opposing faces of the press heads 1, 2, and secured thereto, and the form 3 including a body U shaped in general form and an expander 5 in the form of a plate or sheet within the body and mounted to project different distances through the open side of the U formation of the body 3 to conform to shirt sleeves of different widths, and to draw or stretch the shirt sleeves widthwise during the outward shifting of the expander.

The bend of the U formation of the form 3 is opposed to the bend of the wrapper 4. The wrapper 4 is shaped to provide recesses complementary to the body 3 of the wrapper, and the outer portions of the sides of the wrapper converge inwardly to coact with the edges 6 of the sides of the form and to press at 7 against the opposite sides of the projecting portion of the expander 5.

As here illustrated, the press heads 1, 2 are provided with supporting plates or brackets 8 on their outer faces, these brackets being hinged

together at 10 to a bracket 11 forming part of the machine frame, beyond the bend of the U formation of the wrapper. The heads have a pivotal or scissors-like closing movement. The plates are secured to the press heads by screw bolts 11A. The heads 1, 2, are internally heated in any suitable manner. The sides of the wrapper are in heat conducting relation to the press heads. Each form 3 is spatulate in general form and the edge at the bend of the U formation tapers or inclines outwardly from the upper end of the form to the lower, while the other or front edge is substantially vertical, all to conform to the taper of shirt sleeves from the cuff to the shoulder.

The forms are mounted on a carriage 13 suitably mounted on a base 14 of the frame and have a fore and aft shifting movement to carry the forms into and out of position between the press heads 1, 2. The press heads 1, 2, are of sufficient height to press the longer shirt sleeves from the shoulder to the cuffs. In pressing shorter sleeves, the press heads lap on the front, back and yoke of the shirt, which are subsequently pressed on different machines.

As here shown, the press heads of each pair are movable from open position, Figure 3, into closed position, and then subsequently the press heads 1 are moved into pressing position towards the heads 2, so that both heads are in the position shown in Figure 2. Thus, during the pressing operation occurring when the press heads 2 move into pressing position, the press heads 2 move in an arcuate path about the axis of the hinges 10. The compression and deformation of the pad during the arcuate movement causes slack to develop at S, Figure 7, beyond the edges at the open side of the U formation of the body of the form, which slack is taken up by the expander, as will be hereinafter set forth. The bend of the U formation of the wrapper 4 is reinforced against undue warping or creasing by a backing strip 16 supported from the bracket 11.

As seen in Figure 4, each form 3 is double walled and formed up of two sheets of metal spaced apart and secured together to form an internal steam chamber 21, to which steam is supplied to heat the form, or the body thereof, in any suitable manner, as through inlet and return pipes P, P1. The body of the form is covered by a padding 22. The padding 22 takes the form of a sleeve folded U shaped, and the layer of the padding around the inner face of the bend of the U formation of the form is held from undue displacement as by a rod 23 anchored, as by a screw 24, Figure 1 to the carriage 13, the rod extending upwardly into the form along the bend of the U formation. The rod is resilient and biased to press the internal layer of the padding toward the inner face of the body of the form at the bend of the U formation. Heretofore in machines where the garment sleeve has been dressed or sleeved on the form, the form has been unprovided with a pad. In the present machine, the body of the form being flat or spatulate with double walls of thin sheet metal spaced apart to provide a chamber for a heating medium, provides a construction by which the paddings on the form and on the expander are kept dry.

Each expander 5 is formed of a strip of sheet metal covered by a padding 26. It is supported and operated by mechanism including an angle lever 27 pivoted at 28 at its angle to the carriage 13. This mechanism embodies resilient means

to cause the expander to have a yielding follow-up action in the sleeve.

In the illustrated embodiment of the invention, the resilient means is embodied in one arm 29 of the angle lever, which arm extends upwardly into the body of the form and is pivoted to the expander 5 at 30 between the upper and lower ends of the expander, the arm 29 being a leaf spring. The other arm of the lever 27 extends forwardly 10 in front of the form where it is provided with a handle 31. The pivoting of the arm 29 to the expander between the upper and lower ends thereof causes the expander to have an equalizing action to conform to the sleeve, and the resilient arm 29 causes the expander to have a follow-up action. After the sleeve is dressed on the form when the form is in its position out from between the press heads, the expander is operated to stretch the shirt sleeve widthwise.

The operating levers 27 for the expanders may be operated in any suitable manner, and as here shown they are operated manually, or their operation controlled. They are held in their operated position by friction latches 32. Each latch 32 is 20 pivoted at 33 to the forward extending arm of the companion lever 27 and has a shoe 34 coacting with an arcuate friction face 35 in a curve struck from a center eccentric to the pivot 28 of the lever 27. The movement of each latch is against 25 a returning spring 36. The latches are released 30 by power means hereinafter referred to.

The power utilized for operating the movable elements of the sleeve press is compressed air. The actuators or motors are of the cylinder and piston type, and the flow of air thereto controlled by valves.

The numeral 40, Figure 1, designates a cylinder and piston motor used to shift the carriage 13 to carry the forms into position between the 40 pressing elements or heads, and 41 designates a cylinder and piston motor for shifting the carriage to carry the forms out of position between the 45 pressing elements. The motor 40 is of greater capacity, or strength, than the motor 41 and when energized overrules the motor 41. The piston rod 42 of the motor 40 is connected at 43 to one of a pair of swinging links 44. These links are pivoted at their lower ends at 45 to the base of the frame 1, and at their upper ends at 46 to the carriage 13. The links 44 are paired with another set of links 47, the links 44 and 47 being 50 arranged to have a parallelogram action to swing the carriage 13 horizontally to carry the forms into and out of position between the press heads 1, 2. The piston rod 48 of the motor 41 is 55 connected at 49 to one of the links 44. The momentum of the carriage 13, when it approaches the limit of its outward movement, is damped by a dash pot 50, the movable member of which has a head 51 arranged in the path of a shoulder 52 on one of the links 44. The actuating mechanism, 60 for the carriage 12 forms no part of the invention.

The motor for effecting the movement of the 65 press heads 1 about the axis of the hinges 10 into straight position, is here shown as a cylinder and piston motor 53, Figure 2, the rod 54 of which is pivoted to the joint of the toggle links 55 and 56, the outer ends of which links are pivoted at 70 57 and 58 to the heads 1.

When the motor 53 is energized, the toggle links 55, 56, are straightened from the position shown in Figure 3 to that shown in Figure 2, and the press heads 1 are moved into the position 75 shown in Figure 2 before the press heads 2 are

swung about the axis of the hinges 10 into pressing position.

The motors for actuating the heads 2 are also cylinder and piston motors 59, suitably supported by the main frame; the piston rods 60 of which thrust against the outer sides of the heads 2 to move the heads about the pivots 10.

The latches 32 for the operating levers 27 of the expanders are released or kicked off by air operated motors 61 of the cylinder and piston type, there being one motor for each lever 27. The piston rods 62 of the motors act to thrust against the latches 32 to release the same and also to actuate the levers 27 to withdraw the expanders into the body of the form. The motors 61 are carried by and are movable with the carriage 13. The flow of power or compressed air to the cylinder and piston motors is controlled and cycle timed in any well known manner, not forming part of this invention. As it is old to cycle time the operations of machines, particularly laundry machines, it is thought that a description of the air control and timing is unnecessary.

The frame and mechanism carried thereby are enclosed in a casing C. The upper portion of the casing CA enclosing the press heads is provided with suitable door openings or slots in the front side thereof through which the forms 3 shift when moving into and out of position between the press heads.

In the general operation of the machine, the operator pulls the sleeves over the forms when the forms are out of between the pressing elements, or in the position shown in Figures 3 and 5, and clamps the cuffs on the upper ends of the forms by means of a suitable cuff clamp CL. The operator then operates the expanders by means of the levers 31, thus pulling the sleeve taut in a transverse direction. The operator then operates a control or push button which starts a timer in operation, first permitting air to pass to the cylinder 40 and move the carriage 13 from the dotted line position, Figure 1, into the full line position between the pressing elements, or from the position shown in Figure 3 to that shown in Figure 2. Air then, due to the timing mechanism, passes to the cylinder 53 to straighten the toggle links 55, 56, and move the press heads 2 from their outward pivoted or hinged position into straight position. The air then flows to the cylinders of the motors 59, moving the press heads 2 about their hinged axes towards the press heads 1. The time the heads remain closed is determined by the timer as the timer opens a suitable valving exhausting all the cylinder and piston motors, except the motor 41, and the air being exhausted from the stronger motor 40, permits the weaker motor 41 to act to shift the carriage 12 from outward position between the press heads into the broken line position, Figure 1, when the shirt sleeves are removed from the forms, a new shirt placed thereon, and the operation repeated. During the pressing of the shirt sleeves, and particularly the arcuate movement of the heads 2, the pressure is first applied to the portion of the sleeve on the body of the form, and later to the portion of the sleeve overlying the projected part of the expander. Because of the deformation or compression of the portion of the padding on the body of the form before the pressure is applied to opposite sides of the expander, slack in the shirt sleeve is liable to occur at S at the open edges of the body of the form. As the press heads are not

in final clamping action, this slack is taken up by the resiliency of the spring arm 29 moving the expanders farther outward.

Owing to the shape of the wrapper conforming to the form and the expander, sleeves of different lengths and widths are press ironed, throughout the length and width of the sleeve, with the exception of an unnoticeable thin line along the rear edge of the sleeve.

What I claim is:

1. In a sleeve pressing machine, opposing pressing heads having relative opening and closing movements, a form on which the sleeve is dressed shiftable into and out of position between said heads when open, a flexible sheet metal wrapper U shaped in general form in cross section and having the arms or branches thereof, overlying the opposing faces of the heads, the form including a spatulate body U shaped in cross section arranged with the bend of the U formation toward that of the wrapper, and an expander in the body and shiftable edgewise through the open edge of the body, the branches of the wrapper being shaped to provide recesses complementary to the body, and the branches of the wrapper at the open side of the U formation being converged toward each other to coact with the edges of the side of the body and with the side faces of the expander.

2. In a sleeve pressing machine, opposing pressing heads having relative opening and closing movements, a form on which the sleeve is dressed shiftable into and out of position between said heads when open, a flexible sheet metal wrapper U shaped in general form in cross section and having the arms or branches thereof, overlying the opposing faces of the heads, at least one of the heads being hinged on an axis located outward from the bend of the U formation of the wrapper, whereby the head opens and closes with a scissors-like action, the form including a spatulate body U shaped in cross section with the bend of the U formation toward that of the wrapper and an expander in the body, the branches of the wrapper being shaped to provide recesses complementary to the body, and the branches of the wrapper beyond the recesses being converged toward each other to coact with the edges of the body at the open side thereof and with the side faces of the expander.

3. In a sleeve pressing machine, opposing pressing heads having relative opening and closing movements, a form on which the sleeve is dressed shiftable into and out of position between said heads when open, a flexible sheet metal wrapper U shaped in general form in cross section and having the arms or branches thereof, overlying the opposing faces of the heads, at least one of the heads being hinged on an axis located outward from the bend of the U formation of the wrapper, whereby the head opens and closes with a scissors-like action, the form including a spatulate body U shaped in cross section with the bend of the U formation toward that of the wrapper and an expander in the body, the branches of the wrapper being shaped to provide recesses complementary to the body, and the branches of the wrapper beyond the recesses being converged toward each other to coact with the edges of the body at the open side thereof and with the side faces of the expander, and operating mechanism for the expander including a resilient member loaded to impart a follow-up action to the expander as the heads close on the form.

4. An expanding form for sleeve ironing presses of the type including opposing platen press heads having relative opening and closing movements, a form on which the sleeve is dressed shiftable into and out of pressing position between said heads when open, and a flexible sheet metal wrapper U shaped in general form in cross section having the arms thereof overlying the opposing faces of the press heads, the expanding form including a spatulate body U shaped in cross section arranged with the bend of the U formation toward that of the wrapper, and an expander in the body and shiftable edgewise through the open edge of the body, the wrapper being shaped to provide recesses complementary to the body, and the sides of the wrapper at the open side of the U formation being converged toward each other to coact with the edges of the side of the body and with the side faces of the expander extending out of the body, and operating mechanism for the expander.

5. An expanding form for sleeve ironing presses of the type including opposing platen press heads having relative opening and closing movements, a form on which the sleeve is dressed shiftable into and out of pressing position between said heads when open, and a flexible sheet metal wrapper U shaped in general form in cross section having the arms thereof overlying the opposing faces of the press heads, the expanding form including a spatulate body U shaped in cross section arranged with the bend of the U formation toward that of the wrapper, and an expander in the body and shiftable edgewise through the open edge of the body, the wrapper being shaped to provide recesses complementary to the body, and the sides of the wrapper at the open side of the U formation being converged toward each other to coact with the edges of the side of the body and with the side faces of the expander extending out of the body, the closed edges of the U formation of the wrapper being inclined from the upper to the lower end of the wrapper, and the closed edge of the body of the form being complementally tapered, and operating mechanism for the expander.

6. An expanding form for sleeve ironing presses of the type including opposing platen press heads having relative opening and closing movements, a form on which the sleeve is dressed shiftable into and out of pressing position between said heads when open, and a flexible sheet metal wrapper U shaped in general form in cross section having the arms thereof overlying the opposing faces of the press heads, the expanding form including a spatulate body U shaped in cross section arranged with the bend of the U formation toward that of the wrapper, and an expander in the body and shiftable edgewise through the open side of the body, the walls of the body being double providing a heating chamber within the same, the wrapper being shaped to provide recesses complementary to the body and the sides of the wrapper at the open side of the U formation being converged towards each other to coact with the edges of the sides of the body and with the side faces of the expander extending out of the body, and operating mechanism for the expander.

7. An expanding form for sleeve ironing presses of the type including opposing platen press heads having relative opening and closing movements, a form on which the sleeve is dressed shiftable into and out of pressing position between said heads when open, and a flexible sheet metal wrapper U shaped in general form in cross section

having the arms thereof overlying the opposing faces of the press heads, the expanding form including a spatulate body U shaped in cross section arranged with the bend of the U formation toward that of the wrapper, and an expander in the body and shiftable edgewise through the open edge of the body, the wrapper being shaped to provide recesses complementary to the body, and the sides of the wrapper at the open side of the U formation being converged toward each other to coact with the edges of the side of the body and with the side faces of the expander, said operating mechanism including a resilient instrumentality effecting a follow-up action of the expander to take up slack in the sleeve during the final closing movement of the press heads and the wrapper on the form and the shirt sleeve thereon.

20 8. An expanding form for sleeve ironing presses of the type including opposing platen press heads having relative opening and closing movements, a form on which the sleeve is dressed shiftable into and out of pressing position between said heads when open, and a flexible sheet metal wrapper U shaped in general form in cross section having the arms thereof overlying the opposing faces of the press heads, the expanding form including a spatulate body U shaped in cross section arranged with the bend of the U formation toward that of the wrapper, and an expander in the body and shiftable edgewise through the open edge of the body, the wrapper being shaped to provide recesses complementary to the body, and the sides of the wrapper at the open side of the U formation being converged toward each other to coact with the edges of the side of the body and with the side faces of the expander extending out of the body, and operating mechanism for the expander, the operating mechanism including a motion transmitting lever having a resilient arm located to be loaded during the extending action of the expander and hence operating to have a follow-up movement 40 during the final closing of the wrapper and press heads to take up slack developed in the shirt sleeve during the final closing.

9. In a sleeve ironing press of the type including opposing platen press heads having relative opening and closing movements, a form on which the sleeve is dressed shiftable into and out of pressing position between said heads when open, a flexible sheet metal wrapper U shaped in general form in cross section and having the arms 50 or branches thereof overlying the faces of the opposing press heads, the form including a spatulate body U shaped in cross section arranged with the bend of the U formation toward that of the wrapper, and an expander in the body and shiftable edgewise through the open side of the body, the wrapper being shaped to provide recesses complementary to the body, and the sides of the wrapper at the open side of the U formation being converged toward each other to coact 65 with the edges of the branches of the body and with the sides of the expander extending out of the body, a padding on the body, at least one of the press heads being hinged on an axis extending along and outside of the bend of the U formation of the wrapper, whereby at least one of the press heads has a scissors-like opening and closing movement, and an operating mechanism for the expander including a resilient instrumentality operable to impart a follow-up 70 movement to the expander to take up slack in

the shirt sleeve on the form at the open side of the form as the press heads finally close under the scissors-like action.

10. An expanding form for sleeve ironing presses of the type including opposing platen press heads having a relative opening and closing movement, a form on which the sleeve is dressed shiftable into and out of position between the heads when open, the expanding form including a spatulate body U shaped in cross section and an expander platen in the body and shiftable edgewise through the open side of the body, a padding for the body in the form of a sleeve enclosing the body and folded U shaped to conform to the U formation of the body, and a resilient rod extending endwise of the form and loaded to press the portion of the padding overlying the inner face of the U formation of the body toward the bend of the U formation.

11. An expanding form for sleeve ironing presses of the type including opposing platen press heads having a relative opening and closing movement, a form on which the sleeve is dressed shiftable into and out of position between the heads when open, the expanding form including a spatulate body U shaped in cross section and an expander in the body and shiftable edgewise through the open side of the body, the body being of thin sheet metal and having double spaced walls providing a chamber for a heating medium, padding entirely enclosing the body and lying on the outer faces of the double walls thereof, and padding enclosing the expander on the opposite sides and edges thereof.

ERNEST DAVIS.
